UNITED STATES PATENT OFFICE.

ROBERT MALZAHN, OF WESTBEND, WISCONSIN.

PURSE.

SPECIFICATION forming part of Letters Patent No. 717,880, dated January 6, 1903.

Application filed March 29, 1902. Serial No. 100,554. (No model.)

To all whom it may concern:

Be it known that I, ROBERT MALZAHN, a citizen of the United States, and a resident of Westbend, in the county of Washington and State of Wisconsin, have invented certain new and useful Improvements in Purses; and I do hereby declare that the following is a full, clear, and exact description thereof.

The object of my invention is to save cost in the manufacture of hinge-frame purses and to provide such purses having seamless bodies, said invention being hereinafter more particularly set forth and subsequently claimed.

15 Figure 1 of the drawings represents a plan view of the body-piece of a purse in accordance with my invention, and Fig. 2 an end view of the purse.

Referring by letter to the drawings, A indicates the pliable body, and B each of the metal frame-sections of a purse in accordance with my invention, said frame-sections being hinged together at opposite ends and herein shown provided with locking-knobs C, such as are common in the art; but various other well-known means may be employed in connection with said frame-sections to hold the purse closed. Purse-body A is a single piece of pliable material blanked to have narrow ends notched at their extremities, and which with the wider middle portion have longitudinal and oblique edges. The polygonal edges of the body-piece are made fast to the frame-sections B of the purse and are each folded 35 on lines diverging from a common center, as indicated by dotted lines in Fig. 1, there being a middle outward fold, adjacent inward

folds on lines extending from said center to points between corners of oblique edges of said end, and outward folds on lines from the aforesaid center to intersections of longitudinal end edges and oblique edges of the widest portion of said body-piece. The purse-body being a single piece shaped and folded as herein set forth, no stitching is required in making a strong, durable, and economical purse.

Having thus described my invention, what I claim as new, and desire to secure by Letters Patent, is—

A hinge-frame purse, the body of which is a single piece of pliable material blanked to have narrow ends angularly notched at their extremities and which with the wider middle portion of the piece have longitudinal and oblique edges, said ends being each folded outward on a center longitudinal line, inward on lines extending from said center to points between corners of oblique edges of said end and outward on lines from the aforesaid center to intersections of longitudinal end edges and oblique edges of the aforesaid body-piece, the polygonal edges of this body-piece being made fast to the hinge-frame sections of the purse.

In testimony that I claim the foregoing I have hereunto set my hand, at Westbend, in the county of Washington and State of Wisconsin, in the presence of two witnesses.

ROBERT MALZAHN.
